Primary Examiner — Richard E Chilcot

(74) Attorney, Agent, or Firm — Pearne & Gordon LLP

(57) **CLAIM**

The ornamental design for outboard motor, as shown and described.

DESCRIPTION

1. Outboard motor

1.1 : Front

1.2 : Back

1.3 : Right

1.4 : Left

1.5 : Top

1.6 : Bottom

1.7 : Perspective

1.8 : Perspective

1 Claim, 8 Drawing Sheets(56)
